ATTORNEY

UNITED STATES PATENT OFFICE.

WILLIAM SHAW, OF LAKewood, OHIO, ASSIGNOR TO NATIONAL CARBON COMPANY,
OF CLEVELAND, OHIO, A CORPORATION OF NEW JERSEY.

PIGTAIL CONNECTION.

1,189,179.

Specification of Letters Patent. Patented June 27, 1916.

Application filed August 6, 1912. Serial No. 713,570.

To all whom it may concern:

Be it known that I, WILLIAM SHAW, a resident of Lakewood, in the county of Cuyahoga, in the State of Ohio, have invented new and useful Improvements in Pigtail Connections, of which the following is a clear and exact description.

This invention relates to brushes and to the fastening of the pigtail thereto.

10 One object of the invention is to firmly secure the pigtail to the brush so that there will be minimum contact resistance.

Another object is to secure the pigtail to the brush in such manner that it can not 15 work loose in practice, but to arrange it so that it may be removed and attached to another brush when the first brush is no longer serviceable.

Other objects will appear in the appended 20 description.

In the drawings: Figure 1 is a view of a brush having a pigtail connected in accordance with my invention. Fig. 2 is a view of the back side of the brush shown in Fig. 25 1. Fig. 3 is a section taken in the plane A—A of Fig. 1. Fig. 4 is a top view of a brush in which the pigtail extends through a hole in the top. Fig. 5 is a section of a brush having a metallic cup at one end of the connection. Fig. 6 is a section of a brush 30 having a metallic cup at both ends of the connection. Fig. 7 is a view of the nut with the lug to prevent it from turning. Fig. 8 is a view of the bent wire used to prevent the 35 screw connection from loosening. Fig. 9 is a view of the metal cup.

Referring to Figs. 1, 2 and 3, a hole is drilled or otherwise formed in a brush 1 and the two ends are counterbored as at 2 and 40 3. A groove 4 extends from the counterbore 2 to the top to receive the pigtail so that the connection will not interfere with the brush moving freely in the brush holder.

One end of the pigtail is coiled around 45 45 in the counterbore 2 and a screw 6 is inserted in the hole to extend through the coiled end. A nut 7 having a lug is placed in the counterbore with the lug extending into the groove 4. The screw 6 is then turned to screw into the nut 7 and tightly compress the end of the pigtail against the bottom of the counterbore. Diverging holes 8 are drilled in the brush so as to lie in the plane of the slot in the screw head. A wire 9 is 50 bent somewhat into U-shaped form as shown

in Fig. 8 and is then driven or pressed into the holes with the middle portion in the slot of the screw head. The lug on the nut 7 prevents it from turning and the wire in the slot prevents the screw from turning so 60 that the connection cannot work loose. The wire 9 bends to conform to the shape of the holes 8 in the driving process and cannot come out. When the brush is worn out the connection can be readily removed by breaking the brush. The pigtail and the other parts can be used again in another brush. 65

In Fig. 4 a hole or channel 10 is drilled to extend into the counterbore. This serves the same purpose as the groove or channel 70 4 in Fig. 1.

In some cases it may be desirable to put a close fitting cup 11 in the counterbore as shown in Fig. 5. This cup has a slot 12 to receive the lug on the nut 7. The head of 75 the screw in Fig. 5 is beveled and the counterbore is beveled to fit it.

In Fig. 6, cups 11 are used in both counterbores. The connection is otherwise the same 80 as in the other figures.

This invention is obviously not limited to a particular form of pigtail. The term pigtail as used in the specification and claims is intended to refer to any type.

Having described my invention what I 85 claim is:

1. In current collectors, a brush, a screw having a slotted head, a nut engaging the screw, a pigtail secured to the brush by the said screw and nut, and a U-shaped 90 member in said slot having diverging ends extending into the brush to prevent it from turning.

2. In current collectors, a brush having a hole therethrough, one end of the hole being enlarged, a channel leading into the hole, a pigtail extending through the channel into the hole, a nut having a lug extending into the channel, a screw in the hole engaging the nut and a bail fitting in the slot of the screw 95 head and extending into the brush to prevent it from turning. 100

3. In current collectors, a brush having one transverse and two diverging holes, one end of said first mentioned hole being counterbored, a pigtail having one end in the counterbore, a nut to hold the pigtail therein, a screw extending through the first mentioned hole and engaging the nut and a bail fitting in the slot of the screw head and ex- 105 110

tending into the diverging holes to prevent said screw from turning.

4. In current collectors, a brush having a hole therethrough one end of the hole being counterbored, a metal cup in the counterbore, a pigtail having one end in the cup and means to hold the pigtail and cup in place.

In testimony whereof I have hereunto signed my name.

WILLIAM SHAW.
